UNITED STATES PATENT OFFICE.

LOUIS I. KEITZ, OF CINCINNATI, OHIO.

VALVE.

Application filed December 22, 1923. Serial No. 682,279.

To all whom it may concern:

Be it known that I, LOUIS I. KEITZ, a citizen of the United States, residing at Cincinnati, in the county of Hamilton and State of Ohio, have invented new and useful Improvements in Valves, of which the following is a specification.

This invention relates to a valve structure designed for use on internal combustion engines, utilizing either steam or gas as the propelling agent, and an object of the invention is to provide a valve structure which will eliminate many of the inconveniences contingent with the use of the approved types of tappet valve constructions, and one which is constructed to provide firm, secure seating at all times, and eliminate leakage through improper seating of the valve.

Another object of this invention is to provide a valve structure as specified, which includes a slideable valve sleeve provided with ports adapted to register with suitable cylinder ports for controlling the inlet or exhaust of fuel into or from the cylinder structures of the engine, and to provide a novel form of locking structure which will lock the valve structure in adjusted positions against accidental movement under pressure.

Other objects of the invention will appear in the following detail description, and in the accompanying drawings wherein:

Figure 1—is a vertical section through an engine showing the improved valve structure applied thereto.

Figure 2—is a horizontal section on the line 2—2 of Figure 1.

Figure 3—is a side elevation of the sliding valve.

Figure 4—is a side elevation of the locking stem for locking the valve in adjusted positions.

Figure 5—is an edge elevation of the locking stem structure.

Figure 6—is a detail side elevation of a guide plate employed in the valve structure.

Referring more particularly to the drawings, the improved valve structure is illustrated as associated with an internal combustion engine 1 which is of any approved type, the walls of which are provided with suitable ports 2 to permit the ingress or egress of fuel into or from the cylinder, it being understood that both the intake and the exhaust valve structures are similar in construction and that only one is shown

in the drawings, and will be hereinafter described.

The valve structure comprises a valve sleeve 5 which is fitted in a valve housing 3 formed on the engine structure 1. The sleeve 5 is provided with suitable ports 6 which register at all times with the ports 2 and with a relatively large port 7 diametrically opposite to the ports 6 which latter port is adapted to communicate either the intake or exhaust manifold.

A sliding valve 8 is mounted in the sleeve 5 and is substantially semi-cylindrical in shape, being provided with ports 9 adapted to register at predetermined intervals with the ports 2 and 6. The upper end 10 of the sliding valve 8 is disc-like in construction, and has an inverted cup 11 formed centrally thereon in which a spiral spring 12 is mounted. Spiral clearance spring 12 engages against the upper horizontal member 13 formed on the locking stem structure 14, and it is coiled about the end 15 of the stem which projects above the member 13 and extends through the cup 11. A nut 16 or other suitable obstruction may be mounted upon the upper end of the stem 15 for limiting the movement of the valve 8 relative to the locking stem 14. The inner edges 17 of the valve 8 are slightly inclined, as clearly shown in Figure 3 of the drawings, and they are adapted to engage the slightly inclined edges 18 of the substantially rectangular locking member 19 on the stem 14 so that when the stem 14 is in its uppermost position the valve 8 will be forced against the interior of the valve sleeve 5 for clamping and locking the spiral valve in position.

The member 13 at the upper end of the locking member 19, and the horizontal member 20, at the lower end of the rectangular locking member 19 are substantially circular in plan, and engage against the inner concaved surface of the sliding valve 8 co-operating with the inclined edges 18 in locking the valves in position. A substantially semi-cylindrical guide plate 21 is fitted in the sleeve 5, and is of substantially the same thickness as the sliding valve 8. The guide plate 21 has a dowel 22 carried by its lower end which fits in a suitable recess in the valve housing 3. A suitable cover 4 is provided for enclosing the upper end of the valve structure, as clearly shown in Figure 1.

The locking stem 14 extends downwardly

through the housing extension 3, and its lower end projects into a tappet 23 carried by the crank-case of the engine. The lower end of the stem 14 rests upon an operating pin 24 which is yieldably supported within the tappet 23 by means of the tension spring 25. An adjusting nut 26 is threaded into the tappet for adjusting the position of the pin 24 and consequently, regulating the tension of the spring 25. A suitable rocker 27 is provided which is operated by the cam 28 for operating the valve structure. A suitable opening spring 29 is coiled about the pin 14 and has one end engaging against the housing 3 and the other end engaging a suitable pin or support 30, carried by the stem 14.

In operation, when the valve is in closed position, as shown in Figure 1 of the drawings, the sliding valve 8 is wedged tightly against the sleeve 5 and the ports 2 and 6 are held closed. When the cam 28 rotates into releasing position, the same allows the rocker 27 to drop, permitting the spring 29 to reflex which moves the locking stem 14 downwardly, releasing the clamping pressure against the sliding valve 8, which permits the spring 12 to reflex and allows the valve 8 to drop to bring the ports 9 therein in registration with the ports 6 and 2. The valve is lifted to closed position by the upward movement of the stem 14, and by engagement of the member 13 with the top 10 of the valve, and after the valve has been lifted it is wedged in closed position, by the co-engaging of the inclining surfaces 17 and 18.

It is, of course, to be understood, that the invention may be constructed in various other manners and the parts associated in different relations, and therefore, I do not desire to be limited in any manner, except as set forth in the claims hereunto appended.

What I claim is:

1. In a valve as specified, a ported valve sleeve, a sliding valve therein, a locking stem movable relative to the sleeve and sliding valve, said valve and locking stem provided with inclined co-engaging surfaces whereby the locking stem will wedge the valve into clamped locking engagement with the interior of said sleeve at predetermined times.
2. In a valve as specified, a ported valve sleeve, a sliding valve therein, a locking stem movable relative to the sleeve and sliding valve, said valve and locking stem provided with inclined co-engaging surfaces whereby the locking stem will wedge the valve into clamped locking engagement with the interior of said sleeve at predetermined times,

and a clearance spring associated with said valve and locking stem to facilitate port opening movement of the valve.

3. In a valve as specified, a ported valve sleeve, a sliding valve therein, a locking stem movable relative to the sleeve and sliding valve, said valve and locking stem provided with inclined co-engaging surfaces whereby the locking stem will wedge the valve into clamped locking engagement with the interior of said sleeve at predetermined times, a clearance spring associated with said valve and locking stem to facilitate port opening movement of the valve, and adjustable means for moving said locking stem. 75

4. In a valve as specified, a ported valve sleeve, a sliding valve therein, a locking stem movable relative to the sleeve and sliding valve, said valve and locking stem provided with inclined co-engaging surfaces 80 whereby the locking stem will wedge the valve into clamped locking engagement with the interior of said sleeve at predetermined times, a clearance spring associated with said valve and locking stem to facilitate port opening movement of the valve, and a port substantially semi-cylindrical guide plate within said sleeve and co-operating with said sliding valve. 85

5. In a valve as specified, a ported valve sleeve, a substantially semi-cylindrical valve movable therein and provided with ports for registration with the ports in the sleeve, a valve stem extending through said sleeve and substantially semi-cylindrical valve, said 95 semi-cylindrical valve having a bearing at its upper end for receiving the upper end of said stem, said valve stem having a frame-like locking member formed thereon for engagement with said semi-cylindrical valve 100 for locking it in position.

6. In a valve as specified, a ported valve sleeve, a substantially semi-cylindrical valve movable therein and provided with ports for registration with the ports in the sleeve, a 105 valve stem extending through said sleeve and substantially semi-cylindrical valve, said semi-cylindrical valve having a bearing at its upper end for receiving the upper end of said stem, said valve stem having a frame-like locking member formed thereon for engagement with said semi-cylindrical valve 110 for locking it in position, and a clearance spring carried by said substantially semi-cylindrical valve and engaging said stem to facilitate port opening movement of the valve. 115

In testimony whereof I affix my signature.

LOUIS I. KEITZ.
